UNITED STATES PATENT OFFICE

HARRY J. FARRINGTON, OF AUBURNDALE, MASSACHUSETTS

BOX FOR JEWELRY AND THE LIKE

Application filed March 29, 1928. Serial No. 265,681.

This invention relates to improvements in boxes or cases of an ornamental character which are usually covered with plush, leather, or other textile or fibrous material, and are 5 designed for holding such articles as jewelry, safety razors, and other devices intended for personal use.

The principal object of the invention is to provide an ornamental box for jewelry and 10 the like comprising a vertical side wall of structural-shaped material having a web and flanges extending therefrom so positioned that one of the members thereof forms the upper edge of the side wall and presents a 15 rim simulating a thick side wall of massive appearance, with suitable covering material so disposed as to conceal the material of the side wall and also to conceal the exposed surface of the base.

20 Another object of the invention is to provide a box having a side wall of structural shaped, pliable material which can be readily formed in any desired contour.

A further object of the invention is to 25 provide a box comprising a side wall formed of a strip of structural shaped material having a web and flange members, certain of which are provided with notches to permit the strip to be so bent as to provide a wall having a 30 continuous, preferably vertical, outer face and an upper edge presenting a rim simulating a thick wall.

A further object of the invention is to 35 provide a box of the character specified with a covering material enclosing the exposed faces of the base and side wall and firmly secured thereupon, preferably with the edges of the covering material of the side wall and base interposed between the lower edge of the side 40 wall and the base and the opposite edges of the material extending into the body of the box to provide a surface adapted to be frictionally engaged by a suitable filler.

A further object of the invention is to 45 provide a box having a side wall of the character specified in which the base and side wall are made separately, thereby enabling a base to be used, the edge of which will extend beyond the periphery of the side wall, 50 and which may be made to conform to, or to

differ in shape from, the side wall. By virtue of the present invention the base and side walls may be covered separately and thereafter assembled, thus permitting the box to be produced in different shapes and sizes and 55 covering materials to be employed which otherwise would be unavailable.

A further object of the invention is to provide a box having a continuous side wall formed of a structural shaped strip of material having the ends of the outer face member thereof abutting in the same plane and secured together.

Another feature of the invention consists in securing the abutting ends of the continuous side wall together by one of the plate members of a hinge.

These and other objects and features of the invention will more fully appear from the following description and the accompanying 70 drawings and will be particularly pointed out in the claims.

Preferred embodiments of the invention are illustrated in the accompanying drawings, in which,

Fig. 1 is a perspective view of a box having a continuous side wall formed of a channel-shaped strip, with the web of the strip forming the outer member of the side wall and a plurality of tabs upon the base engaging the lower flange of said strip;

Fig. 2 is a detail view in vertical section showing a box of the construction illustrated in Fig. 1 having a covering material applied thereto and a preferred means of securing 85 the base to the side wall thereof;

Fig. 3 is a detail vertical sectional view illustrating the construction of a covered box embodying the invention shown in Fig. 1, illustrating the manner in which the fillers 90 are retained in the box and cover;

Fig. 4 is a detail perspective view of a different embodiment of the invention in which the side wall is in the form of an inverted channel with a suitable covering applied thereto and also showing the base of the box having covering material applied thereto extending beyond the edge of the side wall and bent up against the outer face of the side wall;

Fig. 5 is a detail perspective view of another embodiment of the invention in which the structural shaped strip is in the form of a Z-bar having covering material thereupon and the covered base of the box extending beyond the lower flange thereof and folded around the same;

Fig. 6 is a perspective view of a completed box embodying the invention in which the body and the cover are of like construction;

Fig. 7 is a perspective view upon a smaller scale of a box having a side wall of inverted channel shape formed integral as by die pressing and provided with covering material;

Fig. 8 is a similar view showing a box having a side wall of inverted channel shape formed of a strip of structural material; and,

Fig. 9 is a perspective view of the strip of structural shaped material employed to form the wall of the box illustrated in Fig. 8.

The present invention comprises certain improvements in boxes of the type disclosed in my prior Patent No. 1,217,291, granted February 27, 1917.

One of the essential features of the invention, which is common to all of the embodiments illustrated in the drawings, consists in the production of a box having a continuous side wall of structural shape which will provide a maximum strength for a minimum amount of material, and which will also have an upper edge presenting a rim simulating a relatively thick wall, thus producing a relatively massive and pleasing appearance.

In the construction shown in Figs. 1, 2, 3, and 6, the box comprises a base 1 of sheet material, preferably sheet metal, having a covering 2 which desirably, but not necessarily, extends around the periphery thereof and onto the inner face a sufficient distance to lie beneath the lower edge of the side wall. The side wall comprises a channel-shaped member having a web 3, an upper flange 4, and a lower flange 5, the upper and lower flanges being suitably notched from their edges to, or in proximity to, the web to permit the web to be bent to the desired form to produce a continuous outer face. The notches also are so designed that the edges of those in the upper flange will abut against each other, thereby producing in effect a continuous upper wall edge, which, when covered, simulates a relatively thick wall. The web, when bent into the desired form, presents a continuous outer face and the ends of said web abut in the same plane and are connected together. Likewise, the ends of the lower flange desirably abut against each other in the same plane as illustrated in Fig. 1. Preferably the abutting ends of the web are provided with interengaging means adapted to hold the ends of the strip from displacement during the manufacture of the box and also to increase its rigidity after completion. In

the construction illustrated in Fig. 1, the abutting ends are provided with complementary members of a dovetail joint 6. Suitable means are also provided to secure the abutting ends rigidly together in the completed box. Such means may comprise a plate suitably secured to the abutting ends by interengaging members, by welding, or in any other desired manner. In the preferred construction illustrated each of the abutting ends is provided with one or more inwardly extending tabs 7 cut from and integral with the strip and adapted to engage suitable slots in the connecting plate. Desirably the abutting ends are connected together by the lower plate 8 of a hinge, the tabs 7 extending through suitable slots in the plate and clinched down thereupon, as illustrated more clearly in Figs. 7 and 8.

It will be noted that in the construction illustrated in Figs. 1, 2, 3, and 6, the upper flange presents in effect a continuous upper edge of uniform width simulating a thick wall, while the lower flange provides a relatively wide base for the wall to engage the base of the box. Covering material may be applied to the vertical member, which is to form the vertical outer face of the side wall, after it has been given its structural shape and before the strip is bent to form the contour of the wall.

In the construction shown a sheet of covering material 9 extends beneath the lower flange 5 of the side wall, thence upwardly across the vertical face of the wall, thence over the upper flange 4 forming the upper edge of the wall, around the edge thereof and upon the under face of said flange. The covering material 2 of the base 1 also extends beneath the horizontal flange 5 and beneath the covering 9 of the side wall so that both coverings are interposed between the flange 5 and the base 1. Desirably the covering material is cemented to the base and side wall and the base may be secured to the side wall by cementing the contacting portions of the covering material. Desirably, however, interengaging means are provided for clamping the side wall and base together. In the preferred construction illustrated this is accomplished by providing a plurality of tabs 10 which are connected to the base and are engaged with the side wall structure preferably by being bent over and down upon the lower flange 5 of the side wall. Desirably the tabs 5 are partially cut from and integral with the base plate and are bent upwardly and laterally to engage the horizontal flange 5, as illustrated in Fig. 1.

The inner open face of the channel-shaped member desirably is closed by a collar 11, having a preferably satin covering 12, the lower edge of the collar being provided with laterally extending tabs 13 which rest upon and may be secured to the base. The collar desir-

ably extends vertically and in engagement with the covering material extending over the inner edge of the upper flange which forms the upper edge of the side wall and desirably may project above the upper edge of the side wall a short distance to enter the cover. A suitable filler, which is illustrated in Fig. 3 as a pad 14, may be placed within the collar and held in such position by frictional engagement with the periphery of the pad with the inner face of the collar.

The cover for the box may be of any desired form, but for symmetry in appearance desirably is constructed in a manner similar to or identical with the construction of the body of the box, the collar, however, being omitted. Detailed description of the cover of the box is, therefore, unnecessary. The box may be constructed in a variety of shapes, the walls thereof made of different heights, and the base of the box to conform to, or depart from, the contour of the wall in any desired manner.

A desired construction, which is illustrated in detail in Fig. 3, comprises a top 15 having a covering material 16 secured thereto and extending around the periphery thereof on to its under face, a side wall formed of a channel-shaped strip 17, having inwardly extending upper and lower flanges 18 and 19, and covering material extending along the face of the upper flange across the outer face of the web 17, thence across the face of the lower flange 19, around the edge thereof, and into the body of the cover, and desirably being secured to the under face of the upper flange 18. The flange 19 of the side wall of the cover desirably is of the same width as the flange 4, which forms the upper edge of the side wall, so that when the cover is closed upon the body of the box the projecting portion of the collar 12 will extend across the plane of engagement of the edges of the side walls of the base and cover.

Any suitable filler may be provided for the cover, such for example as a puff which may comprise a frame-work 20 of fibrous material with a web of fabric 21 extending around the periphery thereof and secured thereto, said puff being adapted to be snapped into the cover and retained therein, as illustrated in Fig. 3. Of course, the box and its cover may be provided with any sort of pad or lining.

It will be obvious that in constructing the cover the upper plate of the hinge member may be employed to secure the abutting ends of the web of the side wall together, as heretofore described, and the complementary hinge plates will be connected together by the usual pintle.

A different embodiment of the invention is disclosed in Figs. 7, 8, and 9, in which the side wall is in the form of an inverted channel, the web of which constitutes the upper edge 65 of the side wall and may be of any desired

width to present a rim simulating a thick wall. Fig. 7 shows a construction in which the side wall is formed by punching and stamping the same from a flat sheet of material. In producing a box of the rectangular form illustrated in Fig. 7, a rectangular sheet of the required size is provided and a rectangular central portion thereof cut out. The sheet is thereupon slitted from the corners of the cut-out space to the point which is to form the inner edge 70 of the web of the channel. The sheet may then be pressed by suitable dies into channel form having a configuration corresponding to that of the die. When thus shaped the side wall will present a continuous vertical seam- 75 less face or flange 22, a continuous and seam- less upper edge 23 forming the web of the channel-shaped construction and a downwardly extending flange 24, this flange being in sections by virtue of the notches cut in the 80 sheet to permit the die-shaping thereof.

Desirably the lower edges of the flanges 24 are bent inwardly to provide lips 25 which are adapted to be engaged by tabs 26, which desirably are punched up from and integral 85 with the base 27 of the box as heretofore described. This construction may be covered in the manner heretofore described.

A construction is illustrated in Fig. 8 in which the side wall of the box is of inverted 90 channel form and is constructed from a structural shaped strip of material of inverted channel shape, as illustrated in Fig. 9. This construction comprises a web 28, an outer vertical flange member 29, and an inner flange member 30 which desirably has a laterally extending lower edge 31 which, when the strip is bent to form the box, extends inwardly. Suitable notches 32 are provided in the web member 28 and the inner flange member 30, these notches being so designed as to permit the strip to be bent into the desired form.

In the construction shown in Fig. 9, the web 28 is provided with two notches 33 and 34 separated by a truncated V-shaped projection 35, while the vertical flange 30 and the lip 31 are cut away in the planes of the outer edges of the notches 33 and 34. These notches are made at suitable distances apart to provide 100 sides or ends of the desired length. When the strip is folded, the opposite edges of each notch abut and the V-shaped extension 105 35 fills the corner between the sides and ends to produce an effectively continuous upper edge for the side wall.

In the construction shown in Figs. 7 and 8, the end portions of the web and inner flanges are cut away so that the outer flange 29 extends a sufficient distance therebeyond to permit the attachment of the hinge plate 8 to the abutting ends of the outer flange 29. In this construction, as in that illustrated in Fig. 1, the vertical outer member of the side wall is provided with inwardly extending tabs 110 7 115 120 125 130

which pass through slots in the hinge plate and are clinched down thereupon.

Obviously the base and side wall of the box illustrated in Fig. 8 may be provided with suitable covering as above described. A suitable cover may also be provided, preferably of a construction similar to that of the body of the box in order to produce a symmetrical appearance.

10 In Fig. 4 another embodiment of the invention is illustrated comprising a side wall of inverted channel form comprising a web 36, a vertical outer flange 37, and a vertical inner flange 38. The covering material 39 extends beneath the lower edge of the outer flange of the box, over the outer face of the flange 37, across the web 36 which forms the upper edge of the side wall, and downwardly along a portion of the inner flange 38. In this 20 construction the base 40 of the box, which is provided with a covering 41, extends beyond the periphery of the side wall 39 and is bent upwardly against such wall. In the construction illustrated in Fig. 4, a modified means 25 for attaching the base to the side wall is illustrated which comprises a recess 42 located in proximity to the lower edge of the wall 38 and a tab 43, which is partially cut from the base and bent upwardly and laterally therefrom, extends through the recess 42.

30 In the constructions disclosed in Figs. 3, 7, 8, and 9, the effective width of the inner flange may be less than the width of the outer flange so that the complementary fastening members upon the base and inner flange, when interengaged, may be caused to clamp the lower edge of the outer flange, which constitutes the face of the side wall, firmly upon the base of the box.

35 Fig. 5 illustrates another form of side wall of structural shape comprising a vertical web 44 and laterally extending upper and lower flanges 45 and 46. In this construction the upper flange 45 extends inwardly to provide the side wall with an upper edge presenting a rim simulating a thick wall, while the lower edge extends outwardly from the web 44. The base 47 as shown in this construction 45 extends beyond the outer edge of the flange 46 and together with the covering material 48 of the base is bent around the edge of the flange 46 to form a seam securing the base to the side wall.

50 The foregoing structural shapes, as well as others which might be described, may be employed in accordance with the invention herein disclosed. Obviously side walls of any desired thickness may be constructed and the side walls made of any desired shape, either circular, elliptical, or otherwise curved, rectangular, or irregular in shape, as the members of the flanges and web, or both, may be suitably notched to permit the bending of the material in such a manner as to 55 produce a continuous and uninterrupted

outer face, either of integral construction, or having abutting ends, and the upper edge of the side wall may be caused to present a continuous face, whether integral or formed by the abutting edges of the notches required to produce the desired form. In either instance the structural shape of the wall provides increased rigidity of construction over the side walls of boxes heretofore produced from sheet material and also presents an edge of greater width and of more pleasing appearance.

60 The base, being formed separately and secured to the side wall, desirably projects beyond the periphery of the side wall and may conform in contour thereof, or may be of a different shape. The boxes may be constructed with or without covering material. When covering material is employed it can readily be applied to the base and side walls 65 respectively. As the side wall is made of strips of structural shape, the covering material can be applied thereto with a minimum amount of bending which will permit the use of covering materials which have not hitherto been available for box coverings because of their inherent characteristics would not permit sufficient bending or stretching to enable them to be economically applied by machines 70 designed for such purpose.

75 It will be understood that the selected embodiments of the invention which are disclosed herein are of an illustrative character and are not restrictive, and that various changes in form, construction and arrangement of parts may be made within the spirit and scope of the following claims.

80 Having thus described the invention, what is claimed as new, and desired to be secured by Letters Patent, is:

85 1. An ornamental box for jewelry and the like comprising a base, a continuous vertical side wall of structural shaped material having a web and flanges extending laterally therefrom so positioned that one of the members thereof forms the upper edge of said side wall and presents a rim simulating a thick side wall of massive appearance, covering material on the outer face of said side wall and extending over and around the upper edge thereof, a base having its edge projecting beyond the periphery of said side wall, covering material on the outer face of said base extending around the edge thereof, and beneath the lower edge of said side wall, and means securing said base to said side wall with the base covering therebetween.

90 2. An ornamental box for jewelry and the like comprising a vertical side wall formed of a structural shaped strip of material having a web and flange members, the vertical member thereof being bent to present a continuous outer face of predetermined form, another member extending inwardly therefrom, having notches with the edges thereof

- abutting, forming an upper edge of said side wall and presenting a rim simulating a thick side wall of massive appearance, covering material secured to said strip extending over said rim and the outer face of said side wall and beneath the vertical member thereof, a base, covering material on the outer face thereof extending around the periphery thereof and beneath said side wall, and means securing said side wall and base together. 5
3. A box comprising a vertical side wall formed of a strip of material bent to a predetermined form to present a continuous outer face with its ends abutting in the same plane, a hinge plate secured to the inner faces of and overlying said abutting ends rigidly securing the same together, a base, and means securing said side wall and base together and a cover hinged to said hinge plate. 10
4. A box comprising a vertical side wall formed of a strip of material bent to a predetermined form to present a continuous outer face with its ends abutting in the same plane, inwardly extending tabs partially cut from and integral with said strip located in proximity to the respective abutting ends, a hinge plate having recesses receiving said tabs rigidly connecting said ends together, a cover hinged to said hinge plate, a base, 20 and means securing said side wall and base together. 25
5. A box comprising a vertical side wall formed of a structural shaped strip of material having a web and flange members, the vertical member thereof being bent to present a continuous outer face and having its abutting ends united by a dovetail joint, a base, and means for securing said base to a flange member. 30
6. An ornamental box for jewelry and the like comprising a vertical side wall formed of a structural shaped strip of material having a web and flange members, the vertical member thereof being bent to present a continuous outer face and having its ends abutting in the same plane, inwardly projecting tabs partially cut from and integral with said vertical member located in proximity to said abutting ends, and a plate having recesses receiving said tabs rigidly connecting said ends together, a base, and means for securing said base to a flange member. 40
7. An ornamental box for jewelry and the like comprising a vertical side wall formed of a channel-shaped strip of material with the flanges thereof extending inwardly, the web thereof being bent to present a continuous outer face of predetermined form, with the ends of said web abutting in the same plane, the flanges being notched with the edges of the notches of the upper flange abutting to form a continuous upper edge of said side wall, presenting a rim simulating a thick wall, of massive appearance, a hinge plate secured to and connecting said abutting ends, 50
- a base, means securing said base to the lower flange of said channel, and a cover having a complementary hinge plate, and means pivotally connecting said hinge plates together. 55
8. An ornamental box for jewelry and the like comprising a vertical side wall formed of a channel-shaped strip of material with the flanges thereof extending inwardly, the web thereof being bent to present a continuous outer face of predetermined form, the flanges being notched with the edges of the notches of the upper flange abutting to form a continuous upper edge of said side wall presenting a rim simulating a thick wall of massive appearance, covering material extending over said rim and around the outer face of said side wall and beneath the lower flange thereof, a base having its edge extending beyond the outer face of said vertical wall, covering material on the outer face of said base extending around the periphery thereof and beneath the lower flange of said side wall, and means securing said side wall and base together. 60
9. An ornamental box for jewelry and the like comprising a vertical side wall formed of a channel-shaped strip of material with the flanges thereof extending inwardly, the web thereof being bent to present a continuous outer face of predetermined form, the flanges being notched with the edges of the notches of the upper flange abutting to form a continuous upper edge of said side wall presenting a rim simulating a thick wall of massive appearance, covering material extending over said rim and around the outer face of said side wall and beneath the lower flange thereof, a base having its edge extending beyond the outer face of said vertical wall, covering material on the outer face of said base extending around the periphery thereof and beneath the lower flange of said side wall, and means securing said side wall and base together. 65
10. An ornamental box for jewelry and the like comprising a vertical side wall formed of a channel-shaped strip of material with the flanges thereof extending inwardly, the web thereof being bent to present a continuous outer face of predetermined form, the flanges being notched with the edges of the notches of the upper flange abutting to form a continuous upper edge of said side wall presenting a rim simulating a thick wall of massive appearance, a base, means securing said base to the lower flange of said channel, a vertical collar secured to said base extending along and projecting above the rim of said side wall, and a filler within said box having its edges frictionally engaging said collar. 70
11. An ornamental box for jewelry and the like comprising a vertical side wall formed 75
- 80
- 85
- 90
- 95
- 100
- 105
- 110
- 115

of a channel-shaped strip of material with the flanges thereof extending inwardly, the upper flange forming the upper edge of the side wall and presenting a rim simulating a thick wall, of massive appearance, a filler secured within the upper flange of said wall, means securing the lower flange of said side wall to said base, and a complementary box of like construction hinged thereto and forming a cover therefor.

12. An ornamental box for jewelry and the like comprising a vertical side wall formed of a channel-shaped strip of material with the flanges thereof extending inwardly, the upper flange forming the upper edge of the side wall and presenting a rim simulating a thick wall, of massive appearance, means securing the lower flange of said side wall to said base, and a complementary box of like construction hinged thereto and forming a cover therefor, and a vertical collar secured to said base extending along and projecting above the rim of the lower side wall adapted partially to enter the box-like cover when in closed position, a filler fitting within and held in place by said collar, and a puff secured within said cover by peripheral engagement with the flange forming the wide upper edge of the side wall of said cover.

30 In testimony whereof, I have signed my name to this specification.

HARRY J. FARRINGTON.
